ROBOT PUSH TOY

Charles H. Hardin, Nashville, Tenn., assignor to Kusan,
Inc., Nashville, Tenn.

Filed Feb. 22, 1972, Ser. No. 228,458

Term of patent 14 years

Int. Cl. D21—01

U.S. Cl. D34—15 D

FIG1

FIG3

FIG4

FIG2

FIG. 1 is a front elevational view of the robot push toy, showing my new design;

FIG. 2 is a right side elevational view thereof, the left side being a mirror image thereto;

FIG. 3 is a rear elevational view thereof; and

FIG. 4 is a top plan view thereof.

I claim:

The ornamental design for robot push toy, as shown and described.
